BUILDING

James L. Reid, El Paso, Tex., assignor to The Atlas Building Products Co., El Paso, Tex., a corporation of Delaware

Filed May 8, 1963, Ser. No. 74,811

Term of patent 14 years

(Cl. D13—1)

The other side and rear of the building, not shown, are identical to the side shown in FIG. 2.

The dominant features of my design reside in the portions shown in full line.

I claim:

The ornamental design for a building, as shown and described.
